UNITED STATES PATENT OFFICE.

GLENN A. SHAFFER, OF GREEN BAY, WISCONSIN, ASSIGNOR TO FORT HOWARD PAPER COMPANY, OF GREEN BAY, WISCONSIN, A CORPORATION OF WISCONSIN.

PAPER-ROLL PACKAGE.

Application filed April 14, 1927. Serial No. 183,693.

The invention relates to paper roll packages and has as an object the provision of a package of roll paper which has been brought to a substantially cubical form and retained 5 in such form by wrappings.

It is an object of the invention to provide roll paper such as toilet paper in a form that will utilize carton space to the best advantage.

10 It is a further object of the invention to provide a package of roll paper which will display a label to the best advantage.

It is a further object of the invention to 15 provide a package of roll paper which will be entirely enclosed by wrapping and therefore will reach the user in a condition of cleanliness.

It is a further object of the invention to 20 provide a substantially cubical package of roll paper which will wrap advantageously when sold over the counter by the retailer.

It is a still further object of the invention to provide a method of producing a package provided by the invention.

25 Further objects of the invention will appear from the following description when read in connection with the accompanying drawings showing an illustrative embodiment of the invention and wherein:—

30 Figures 1 and 2 are perspective views showing subsequent steps in the production of the package; and

Fig. 3 is a perspective view of the finished package.

35 As shown in Fig. 1, the invention is applied to a roll 10 of toilet paper which it is desired to wrap in cubical form and to retain in this form until placed in the hands of the ultimate user. According to the method provided 40 by the invention the roll 10 is shown as placed in a form comprising a plurality of plungers 11, 12, 13, 14, each adapted to be forced against the roll through the medium of rods 15, 16, 17, 18 by suitable mechanism not shown.

45 Before placing the roll 10 in the form, strips of wrapping paper 19, 20 are placed in the form in superposed relation in the bottom of the form, the ends 21, 22 and 23, 24 projecting 50 above the plungers, after which the roll 10 is inserted in the form and the plungers are forced toward the roll to the position shown in Fig. 2. The wrapping may then be pulled taut and the ends 23, 24 may be brought over

the top of the roll and pasted, as shown in 55 Fig. 2, after which the ends 21, 22 may be brought over the ends 23, 24 in the position shown in Fig. 3, and pasted.

The cubical package will then be held in its form by the wrappings after the removal of 60 the pressure of the plungers and may be packed for shipment without further treatment if desired. However it is preferred to apply an additional wrapping 25 placed in the remaining direction about the package as 65 shown in Fig. 3 with the overlapping ends pasted as at 26.

The wrapping 25 may bear the label as indicated in Fig. 3. It will be understood however that the label may be printed upon the 70 strip 19 if desired.

The use of the wrapping 25 has the advantage of covering the roll at the corners where the wrappings 19, 20 abut, which corners might otherwise be exposed to soiling during 75 handling of the package. The package illustrated in Fig. 3 will obviously provide a pleasing appearance upon the retailer's shelf and when wrapped for the purchaser will not objectionably advertise the nature of the 80 contents, also, as already stated, packages of paper will occupy a minimum of space in a carton.

Minor changes in the form of wrapping or in the steps of the method for the production of the package may be made within the scope of the appended claims without departing 85 from the spirit of the invention.

I claim:

1. A package of roll paper comprising in 90 combination, a roll of paper substantially cubical in configuration, wrappings passing about said cube in a plurality of directions and retaining the roll in its cubical form.

2. A substantially cubical package of roll 95 paper comprising in combination a roll of paper having substantially cubical configuration, wrappings passed in each of two directions about said cube and overlapping upon the ends of said roll, the ends of said wrappings being secured whereby to retain the cubical form of the roll.

3. A substantially cubical package of roll 100 paper comprising in combination a roll of paper having substantially cubical configuration, wrappings passed in each of two directions about said cube and overlapping upon the ends of said roll, the ends of said wrap-

pings being secured whereby to retain the cubical form of roll and a third wrapping superposed upon the first named wrappings and passing about the roll in substantial part 5 allelism with the turns of paper of which the roll is comprised.

4. A package of roll paper comprising, in

combination, a roll of paper in the form of a parallelopipedon, wrappings passing about said roll in a plurality of directions and retaining said roll in said form. ¹⁰

In testimony whereof I affix my signature.

GLENN A. SHAFFER.
